Specification for Design.

Patented Oct. 11, 1921.

Application filed March 25, 1921. Serial No. 455,651. Term of patent 7 years.

To all whom it may concern:

Be it known that I, NEVA A. SHIPHERD, a citizen of the United States, residing at Omaha, in the county of Douglas and State of Nebraska, have invented a new, original, and ornamental Design for a Computing Apparatus, of which the following is a specification, reference being had to the accompanying drawing, forming a part thereof.

Figure 1 is a plan view of a computing

apparatus, showing my new design. Fig. 2 is a side view of the same.

I claim,—

The ornamental design for a computing apparatus, as shown.

In testimony whereof I have affixed my signature in presence of two witnesses.

NEVA A. SHIPHERD.
